REVERSIBLE DRESS

Alexander Brick, Clayton, Mo.

Application July 21, 1949, Serial No. 106,048

4 Claims. (Cl. 2—74)

1

This invention relates in general to women's apparel, garments, or dresses and more particularly to a reversible dress.

The primary object of the present invention is to provide a dress which may be optionally worn with either the normally front or normally rear portion presented forwardly and which is equally attractive and fits equally well when worn in either way.

It is an additional object of the present invention to provide a reversible dress having properly fitting construction in the sleeve and armhole for fashionably and comfortably accommodating the wearer's arms in either selected position of wear.

It is an additional object of the present invention to provide a reversible dress which is durable in usage and which may be economically constructed.

With the above and other objects in view, my invention resides in the novel features of form, construction, arrangement, and combination of parts presently described and pointed out in the claims.

In the accompanying drawings (two sheets): Figure 1 is a perspective view of a garment constructed in accordance with and embodying the present invention;

Figure 2 is a perspective view of the garment reversed with the back portion presented forwardly;

Figure 3 is a diagram of the patterns for one face of the garment;

Figure 4 is a diagram of the patterns for the other face of the garment;

Figure 5 is a diagram of the patterns for the sleeve;

Figure 6 is a perspective view of a modified type of sleeve forming a part of the present invention; and

Figure 7 is a diagram of patterns for the modified type sleeve.

Referring now in more detail and by reference characters to the drawing which illustrates a preferred embodiment of my invention, A designates a garment or dress having a face 1 which is designed to be opened from top to bottom along its longitudinal median line, being provided with a uniformly spaced series of buttons 2 and matching buttonholes 3, or any other equivalent fastening means, for holding this portion of the garment normally closed. The face portion 1 comprises a skirt portion 4 and an upper or waist portion 5, the latter consisting of two symmetrical sections 6, 6' (see Figure 3), each of which is

provided with a shoulder cutout 7, 7', respectively, and a neck cutout 8, 8', respectively. Centrally of, and adjacent to, their lower margins, each of the sections 6, 6', are gathered, as at 9, 9', to form upwardly extending, open-topped pleats 10, 10', respectively (Figure 1), providing fullness, as at 11, 11', for normally accommodating the wearer's breasts or, when not required for that purpose, lie in an attractively appearing blouse-like fold or pleat.

The lower or skirt portion 4 comprises two symmetrical panels 12, 12', each of which are gathered, as at 13, 13', respectively, adjacent the central portion of their upper margins to form relatively short downwardly extending darts 14, 14', respectively, which are aligned with the pleats 10, 10', respectively, of the waist sections 6, 6', for presenting seemingly continuous lines when the garment is in assembled, completed form (Figure 1).

The upper part of the skirt portion 4 is so taken in by the darts 14, 14', as to enable said skirt portion 4 to fit the wearer's waist and hips in a correctly stylish, yet comfortable manner. In assembled form, the upper margins of the panels 12, 12', are stitched to the adjacent lower margins of the waist sections 6, 6', respectively, in the formation of a waist seam 15.

The other face 16 of the garment A comprises a skirt portion 17 and a unitary waist portion 18 having a neck cutout 19 which exactly matches the neckline formed by the combination of the cutouts 8, 8'. The waist section is also provided with a pair of opposed shoulder cutouts 20, 20', which are the same size and shape as the shoulder cutouts 7, 7', respectively, of the waist sections 6, 6'. It should be pointed out in this connection that this pattern design of the neck lines 8, 8', and 19 and the armhole-forming cutouts 7, 7', and 20, 20', result in a unique type of armhole construction when the garment is sewn together in which the shoulder seams are centrally located on the shoulder of the wearer and the armholes are symmetrical with respect thereto so that the sleeves as will presently be more fully discussed, are truly reversible. Adjacent its lower margin, the waist portion 18 is provided with two spaced gathers, as at 21, 21', to form a pair of upwardly extending pleats 22, 22', which are in the same relative position and in direct correspondence to the pleats 10, 10', respectively of the sections 6, 6', and similarly provide fullness at 23, 23', respectively, for the same purposes.

The skirt portion 17 comprises a pair of symmetrical side or half panels 24, 24', the inner vertical margins of which have a downwardly and

inwardly inclined section 25, 25', respectively extending from the upper margin thereof for a distance equivalent to the length of the darts 14, 14', on the panels 12, 12'. From the lower end of the inclined section 25, 25', the inner vertical margins of the side panels 24, 24', incline downwardly and outwardly, substantially parallel to the outer vertical margins thereof (Figure 4). Disposed between the side panels 24, 24', is a gore 26 having its bottom margin in alignment with the bottom margins of the side panels 24, 24'. The vertical margins of the gore 26 incline downwardly and outwardly from the upper margin for a distance equal to the length of the section 25, 25', and thence descend straight downwardly in mutual parallel relation.

In assembling the face 16 of the garment A, the inner vertical margins of the side panels 24, 24', are stitched to the adjacent vertical margins of the gore 26 to form so-called shaped seams 27, 27', which permit the skirt portion 17 to accommodate the wearer's waist and hips in a comfortable and form-fitting manner in either of the wearable positions of the garment A, as will be shown hereinafter. The upper margin of the assembled skirt portion 17 is then sewed to the lower margin of the waist section 18 in the formation of a waist seam 28, which will be continuous with the waist seam 15 of the front portion 1 when the garment A is in a completely assembled state. The outer vertical margins of the side panels 24, 24', are stitched to the adjacent margins of the panels 12, 12', along longitudinal side seams 29 to complete the skirt formation. The waist section 18 is stitched along its side and upper margins to the adjacent margins of the sections 6, 6', in the provision of side seams 30 and shoulder seams 31.

The shoulder seams 31, as previously pointed out, are disposed approximately centrally along the shoulders of the wearer when the garment A is in use. It is to be particularly noted that upon uniting the waist sections 6, 6' and 18, the shoulder cutouts 7 and 20, and 7' and 20' provide symmetrical armholes 32, 32', respectively. The symmetry in contour of the armholes 32, 32', constitutes a novel and marked departure from that of armholes of conventionally designed apparel.

Set into each of the armholes 32, 32', are symmetrical wrist-length sleeves 33, 33', respectively, having longitudinal sleeve-seams 34. The sleeves 33, 33', furthermore are, preferably, though not necessarily, tapered slightly outwardly and downwardly to provide a small amount at the lower end. At their lower or wrist ends, the sleeves 33, 33', are gathered and stitched to cuffs 35, 35', respectively which are folded back upon themselves in the manner of a so-called French cuff.

The neck cutouts 8, 8', and 19 form a neck opening 36 to the margins of which is secured, as by stitching, a short collar 37 having rounded wing portions 38 presented on the face portion 1 (Figure 1).

Disposed encirclingly about the garment A and in normally covering relationship to the waist seams 15, 27, is a belt 39 having a buckle or clasping member 40, and being supported by a plurality of loops 41 spacedly stitched to the garment A.

In use, the garment A may be worn as shown in Figure 1, with the face portion 1 presented forwardly giving an attractive fashionable appearance of a coat-dress. When desired the garment A may be reversed and worn, as shown in Figure 2, with the face 16 presented forwardly.

In this latter position, it will be seen that an equally attractive appearance is provided, having tailored, unbroken lines, and with the belt 39 disposed to present the buckle 40 forwardly. The fullnesses provided by the pleats 10, 10' and 22, 22', have requisite expansibility for accommodating the curvature of the breast and the upper portion of the back of the wearer in whichever manner the garment A may be worn. The sleeves 33, 33', also reversibly accommodate the wearer's arms equally comfortably and attractively, with the wearer's upper arms and elbows having the same freedom of movement in either selected manner of wearing the garment A. This unique feature is effected through the symmetrical character of the armholes 32, 32', and of the sleeves 33, 33', respectively, attached thereto. As shown hereinabove, the skirt portions 4, 17, by means of the darts 14, 14', and the shaped seams 27, 27', respectively, will correctly fit the wearer's waist and hips in either wearable position, with the length being uniform therearound.

Thus, despite any variations in the anatomical structure of the wearer, such as a greater curvature of breast than of shoulder, and the like, the garment A, will properly conform thereto in either manner worn, with equal attractiveness.

If desired, the garment A may be provided with a pair of close fitting, wrist length sleeves 42 which in either alternate position of wear, will tightly hug the wearer's arms. The upper end of the sleeve 42 is symmetrical and ogee-curved, being similar in this respect to the above-described sleeves 33, 33', for marginal securement, as by stitching, to the margins of the arm-holes 32, 32', of the garment A. The sleeve 42 integrally comprises an upper section 43, of sufficient width to encircle the wearer's arms and having its vertical margins stitched to form a seam 44, and a relatively narrow, lower section 45, which, in wear, will normally be disposed about the outwardly presented portion of the wearer's lower arm. The vertical or side margins of both of said sections 43, 45, taper inwardly and downwardly in substantially the same degree and on each side are connected by short inwardly and upwardly extending transverse margins 46, 46'. Stitched respectively to each of the vertical margins of the lower section 45 is the outer margin of an elongated gusset 47, 47', of general curvate form, having inwardly and downwardly inclined upper margins 48, 48', which are stitched to the margins 46, 46', respectively, of the sleeve 42. The inner margins of the gussets 47, 47', being slightly enlarged at their lower ends, as at 49, 49', respectively, are stitched together to form a longitudinal seam 50, which extends from approximately the elbow to the wrist and is aligned with the seam 44 of the upper section 43 to present an apparent continuous seam. The gussets 47, 47', thus provide a distinctive shaping to the lower arm portion of the sleeves 42 whereby the sleeves 42 will snugly fit the wearer's arms in either of the selected wearable positions of the garment A, with an equally smooth and becoming appearance. In wear, the gussets 47, 47', will be disposed against the inner portion of the wearer's arm and hence not normally presented to view.

From the foregoing, it is evident that the provision of the symmetrical arm-holes 32, 32', will permit the incorporation in the garment of short sleeves, constructed in the same manner as the sleeves 33, 33', but which are cut to any desired length. Such short sleeves will fit the

wearer equally well, just as the sleeves 33, 33', in either wearable position of the garment A.

It should be understood that changes and modifications in the form, construction, arrangement, and combination of the several parts of the reversible dress may be made and substituted for those herein shown and described without departing from the nature and principle of my invention.

Having thus described my invention what I now claim and desire to secure by Letters Patent is:

1. A reversible dress comprising a skirt having front and back portions substantially identical in peripheral contour, a waist having front and back portions substantially identical in peripheral contour and being joined together along side-seams and shoulder seams, said front and back portions of the waist being provided with substantially identical arm cut-outs to form armholes each being symmetrical about a line extending from the upper end of the adjacent side seam to the outer end of the adjacent shoulder seam, and sleeves fitted in said armholes, said sleeves each having a longitudinally extending seam aligned with the adjacent side seam of said waist and being symmetrical with respect to said side and shoulder seams.

2. A reversible dress comprising a skirt having front and back portions substantially identical in peripheral contour and joined by side seams, a waist having front and back portions substantially identical in peripheral contour and joined by shoulder and side seams, said side seams respectively aligned with the side seams joining the front and back skirt portions, said waist portions having arm cut-outs substantially identical to form armholes symmetrical with respect to said shoulder and side seams of said waist portions, and sleeves fitted into said armholes, said sleeves each being symmetrical about its longitudinal axis.

3. A reversible dress comprising a skirt having front and back portions substantially identical in outline and joined by side seams, said front portion of the skirt having pleated folds extending downwardly from the waistline to provide transverse fullness, said back portion of the skirt comprising a plurality of panels joined by shaped seams, said pleated folds and shaped seams being disposed in corresponding relationship, a waist comprising front and back sections substantially identical in peripheral outline and having aligned pleated folds extending upwardly from the lower margin of the waist to provide fullness for the wearer's bust and shoulder blades, said front and back sections having substantially identical arm

cut-outs to form armholes symmetrical about their respective vertical axes, and sleeves fitted in said armholes, said sleeves each having a longitudinally extending under-arm seam aligned with the adjacent side seam of the waist and said sleeves each being symmetrical with respect to such under-arm seam.

4. A reversible dress comprising a skirt portion having front and rear sections marginally secured together along side seams in skirt-formation, said sections being of the same vertical length in all comparable dimensions and having substantially identical amounts of transverse fullness in the region of the hips of the wearer so that the skirt will hang evenly and in proper fitting lines equally well when worn optionally with the rear section to the front or rear of the wearer's body, a waist-portion joined to the upper margin of the skirt-portion said waist-portion having front and rear sections of different style-design joined together along side-seams in waist-formation but being of substantially the same shoulder-to-waist dimensions and having substantially identical amounts of transverse fullness in the region of the bust and shoulder blades so that either of said waist-forming sections will conform properly to the wearer's bust when worn optionally with the rear section to the front or rear of the wearer's body and at the same time such fullness of whichever section is worn to the rear of the wearer's body will fall into a wide symmetrical pleat in which such fullness is substantially concealed while allowing freedom for swinging movement of the wearer's arms and shoulder blades during actual use, said waist-forming sections having armhole cut-outs of substantially the same contour adapted, when matched together in the finished garment, to form armholes which are symmetrical with respect to the waist side-seams, and sleeves set into said armholes, each sleeve being symmetrical to its longitudinal axis, so as to fit the arms of the wearer in the same way when the garment is worn optionally in either front-to-the-front or rear-to-the-front position.

ALEXANDER BRICK.
